GRASS AND WEED DESTROYER

Daniel A. Caylor, Suspension, Ala.

Application July 26, 1943, Serial No. 496,201

1 Claim. (Cl. 126—271.3)

1

My invention relates to the destruction of grass and weeds along the rails and on the bed of railroad tracks, and has among its objects and advantages the provision of an improved weed and grass burner designed to utilize the exhaust gases from a locomotive with which the burner is associated for effectively destroying the growth simultaneously on both sides of the road bed.

In the accompanying drawings:

Figure 1 is a side elevation of a locomotive showing my invention applied thereto.

Figure 2 is a top plan view.

Figure 3 is a front view.

Figure 4 is a sectional detail view illustrating the manner in which the device is incorporated in the smokestack of the locomotive.

Figure 5 is a sectional view of a modified form of weed destroyer control valves.

Figure 6 is a view illustrating a control lever, and

Figure 7 is a view in side elevation of the forward portion of the locomotive, illustrating a slightly different arrangement of the tubes for conveying the exhaust to the road bed.

In the embodiment of the invention selected for illustration, I make use of a steam locomotive 10 of a conventional type. Two tubes 12 are mounted on the locomotive near the forward end of its boiler 14. The tubes 12 are arranged on opposite sides of the boiler and each has one end attached to a flange 16 comprising the base structure of the smokestack 18. The flange 16 is provided with a flange 20 riveted to the smokebox 22 of the locomotive. The flange 16 constitutes a continuation of the smokestack 18 so that the latter has communication with the smokebox 22 in the usual manner.

In Figure 4, the tubes 12 are flanged at 24 and riveted at 26 to the flange 16. This flange has openings 28 coaxial with the tubes 12. Inside the smokestack 18 is mounted a damper 30 which is provided with coaxial shafts 32 arranged transversely of the smokestack and rotatably mounted in bearings 34. This damper is of such diameter as to completely close the smokestack 18 above the openings 28 when the damper is moved to a horizontal position. Means for rotating the damper 30 comprises a crank 36 fixed to one of the shafts 32 and pivotally connected with one end of a rod 38 extending rearwardly to a position inside the cab 40. In Figure 6, the rod 38 passes through an opening 42 in the cab wall 44.

A lever 46 is pivotally connected at 48 with a bracket 50 attached to the wall 44. This lever is provided with a pawl 52 for coaction with a

2

quadrant 54, so that the lever may be latched in different positions to latch the damper 30 in its normally vertical position, its completely closed position, or different intermediate positions.

In Figure 4, each tube 12 is provided with a damper 56. Each damper 56 is provided with a crank 58 pivotally connected with the forward end of a rod 60. The rods 60 extend rearwardly to positions inside the cab 40 and are operated by levers 62 identical with the lever 46 and its associated structure. Thus either or both dampers 56 may be moved to closed or open positions, as desired.

The tubes 12 are contoured to lie close to the boiler 14 and extend rearwardly from the flange 16 and then downwardly between the boiler and the crosshead guide rods 64. Locomotives of the driving wheel arrangement shown are such that sufficient room is available for the tubes 12 when positioned as shown and between the front driving wheel 66 and the rear truck wheel 68. The lower ends of the tubes 12 extend to positions within two or three inches of the rails 70 and are bent rearwardly to angles of about 45 degrees from the vertical. The ends of the tubes are also bent outwardly in substantially the same degree.

In operation, the smokestack 18 may be closed to cause the hot gases to exhaust through the tubes 12. Because of the arrangement of the discharging ends of the tubes 12, the hot gases are exhausted onto the road bed along the rails 70 to effectively destroy any growth adjacent and about the rails.

Figure 5 illustrates a modification in that slide valves 72 are employed in lieu of the pivoted valves 56. The valves 72 are slidably mounted in guides 74 fixed to the flange 76 corresponding to the flange 16. The tubes 78 are fixed to the guide 74 and have communication with the flange 16 through the medium of ports 80 in the guides 74. Each valve 72 has a control rod 82 pivotally connected therewith, which control rods correspond to the rods 60 and may be actuated in the same manner.

As shown in Figure 7, the tubes for conveying the products of combustion and exhaust steam from the locomotive to the road bed, and which are here designated 13, may be arranged to extend directly downward from points immediately above the smoke box 22, to points immediately below the cylinders 15 of the locomotive. At said latter points, the tubes 13 are bent inwardly below the cylinders 15 to position their lower portions in close proximity to the rails 70. The tubes 13 are provided at their lower ends with

nozzles 17 which have their discharge ends located close to the rails 10 and which incline downwardly and rearwardly from the tubes at an angle of approximately 45°.

Without further elaboration, the foregoing will so fully explain my invention, that others may, by applying current knowledge, readily adapt the same for use under various conditions of service.

I claim:

In a steam locomotive having a boiler with a smoke-box and a cab at opposite ends a vertically disposed smokestack connected to the smoke-box with an enlarged rectangular portion between its

upper end and the smoke-box, a valve in the smokestack above the enlarged rectangular portion, tubes connected to the opposite sides of the enlarged rectangular portion and extending down

5 the sides of the smoke-box, a slide valve adjacent each side wall of the rectangular enlarged portion of the stack and controlling the inlet ends 10 of the tubes, and separate operating means leading from each of the said valves to the cab, whereby all the valves may be separately operated.

DANIEL A. CAYLOR.
